William Kilmer

BY Orvis & Bair ATTYS.

UNITED STATES PATENT OFFICE.

WILLIAM KILMER, OF NEWTON, IOWA.

CAN-STOPPER.

1,368,561.

Specification of Letters Patent. Patented Feb. 15, 1921.

Application filed October 28, 1919. Serial No. 234,054.

To all whom it may concern:

Be it known that I, WILLIAM KILMER, a citizen of the United States, and resident of Newton, in the county of Jasper and State 5 of Iowa, have invented a certain new and useful Can-Stopper, of which the following is a specification.

The object of my invention is to provide a can-stopper of simple, durable and inexpensive construction.

A further object of my invention is to provide a stopper for the filling and outlet openings of cans, bottles, and other receptacles, which may be attached to the can, 15 receptacle or the like and instantly moved to position for covering or uncovering the openings therein.

A further object of my invention is to provide a compact arrangement of parts, adapted to occupy a minimum amount of space 20 and arranged to be of sufficient strength to resist accidental knocks against it.

A further object of my invention is to provide a device adapted to automatically 25 seal the opening in the receptacle and to automatically form a closure seal when the receptacle is accidentally jarred.

A further object of my invention is to provide a sealing device for openings in 30 receptacles, adapted to be readily attached to receptacles now in use without altering their form.

With these and other objects in view, my invention consists in the construction, arrangement, and combination of the various 35 parts of the device, whereby the objects contemplated are attained, as hereinafter more fully set forth, pointed out in my claim, and illustrated in the accompanying drawings, 40 in which:

Figure 1 shows a side elevation of the upper part of a can, having a filling opening therein and a spout extending therefrom.

Fig. 2 shows a vertical, transverse, central, sectional view through the device.

Fig. 3 shows a view taken on the line 3—3 of Fig. 1.

Fig. 4 shows a sectional view taken on the line 4—4 of Fig. 1, and

Fig. 5 shows a vertical, central, sectional transverse view of a modified form of my improved device, and illustrating the manner in which my device may be attached to

receptacles which have not been specially made for use therewith.

Referring to the accompanying drawings, I have used the reference numeral 10 to indicate generally an oil can of well-known construction, having a filling opening comprising an upwardly extending collar 11 and a spout 12. A clevis or yoke 13 has pins 14 pivotally mounted in either end, the latter being passed through and secured to the neck or collar 11 by solder or a suitable washer 15.

The central portion of the yoke 13 has an opening therein designed to slidably receive a rod 16 having at its upper end a link 17.

The lower end of the rod 16 is fixed to a closure member designated generally by the reference numeral 18. The closure member 18 is preferably of the shape of an inverted truncated cone, and composed of sheet metal.

Secured to the upper web 19 of the number 18 is a loop of wire 20, which extends beyond the member 19 at either end to form guide loops 21. The guide loops 21 are designed to slidably receive the sides of the yoke 13.

Between the member 19 and the central portion of the yoke 13 is a spring 22. The neck 11 is preferably flared somewhat to correspond with the inclined side walls of the member 18 and to form a liquid-tight joint therewith.

From the construction of the parts just described, it will be seen that when my device is installed on a can or the like, the pressure of the spring 22 against the member 18 will cause a downward, yielding 90 pressure against the side walls of the neck 11, due to the coaction of the yoke 13 and the pivots 14.

If it is desired to remove the closure member 18 from the neck 11, the link 17 95 may be grasped and pulled upwardly which will lift the member 18 clear from the upper edges of the neck 11, thereby making it possible to swing the yoke 13 to one side of the neck where the pressure of the spring 100 will force the bottom of the closure member against the side of the neck and yieldingly hold it from movement or vibration.

When the parts are in the position shown in Fig. 2, it will be seen that vibration or 105 jar imparted to the can 10 will merely cause

the spring 22 to force the closure member 18 more tightly into the neck 11, thereby automatically increasing the liquid-seal, as the tendency to leakage due to splashing of 5 the contents becomes greater.

In the form of the device illustrated in Fig. 5, I have shown an auxiliary device adapted to be attached to the oil cans now in general use, which have screw-threaded 10 necks adapted to coact with threaded sheet metal caps.

In this form of device, the neck 11 is provided at its lower end with threads 23, designed to coact with threads 24 formed 15 in the neck 25 provided with the can.

In order to install this form of the device upon the receptacle, it is merely necessary to remove the cap, which comes with the vessel or can and to screw the neck 11 20 down on the neck of the can.

Fig. 5 also illustrates a slightly different form of closure member, wherein a substantially cup-shaped member 26 receives the spring 22, and the rod 16 and is provided 25 with an outwardly extending flange 27, having slots therein designed to slidably receive the sides of the yoke 18.

From the foregoing description of my improved device, it will be seen that I have 30 provided a stopper for cans, receptacles or the like, which may either be provided with the receptacle when the latter is manufactured or may be readily attached to the receptacle after it is manufactured.

35 In this connection, attention is called to the fact that a band adapted to be remov-

ably mounted on the neck of a bottle may be readily substituted for the threaded portion 23 shown in Fig. 5, so that the device 40 may be readily secured to a bottle.

I have also provided means whereby vibration or jar imparted to the vessel upon which my device is attached will automatically cause the closure member to seat itself more closely, due to the pressure of the 45 spring 22.

All of the parts of my improved device may be made from sheet metal with a minimum number of dies for forming them into required shape. 50

Some changes may be made in the construction and arrangement of the parts of my improved device, without departing from the essential features and purposes of my invention, and it is my intention to cover 55 by my claim any modified forms of structure or use of mechanical equivalents which may be reasonably included within its scope.

I claim as my invention:

In a device of the class described a cup 60 shaped stopper member having opposite projecting ears a yoke having arms projecting through said ears for slidably supporting the stopper member, a rod slidably mounted in the central portion of said yoke 65 and secured to the bottom of said cup shaped member, a spring mounted on said rod between said yoke and the bottom of said cup partially received in the cup shaped member. 70

Des Moines, Iowa, July 18, 1919.

WILLIAM KILMER.
